UNITED STATES PATENT OFFICE.

IRA O. WRIGHT, OF BALTIMORE, MARYLAND, ASSIGNOR, BY MESNE ASSIGNMENTS,
TO THE SYMINGTON COMPANY, A CORPORATION OF MARYLAND.

DRAFT RIGGING.

Application filed April 20, 1922. Serial No. 555,793.

To all whom it may concern:

Be it known that I, IRA O. WRIGHT, a citizen of the United States, residing at the city of Baltimore, in the State of Maryland, have invented certain new and useful Improvements in Draft Rigging; and I do hereby declare the following to be a full, clear, and exact description of the invention, such as will enable others skilled in the art to which it appertains to make and use the same.

My invention relates to draft rigging for railway cars and, generally stated, consists of a center sill tie casting provided with stop members which latter a movable element of the draft rigging gear is designed to engage.

The principal feature of the present invention resides in the provision of a combined stop and tie casting connected to the spaced center sills, said casting having a plurality of bosses acting to space the casting inwardly from said sills, said bosses also being arranged to receive the rivet means for connecting the casting to the center sills.

Another feature of my invention is to provide a combined center sill tie and stop member of maximum strength value for the amount of material used, the bosses formed on said member being advantageously disposed for firmly connecting the casting to the sills in effectively resisting the forces to which the car underframe is subjected.

A further feature of the invention is to provide strong and durable means for transmitting the buffing and draft strains to the center sills, said means including center filler and stop members inwardly spaced from the center sills and arranged for engagement by the respective forward and rear followers of the cushioning mechanism, each of said members having reinforcing means for bracing the wall portions of the casting.

Other objects will be obvious from the description taken with the drawings chosen for purpose of illustrating my invention, and in which—

Figure 1 is a plan view of a railway car rigging associated with spaced draft sills

between which latter are located front and rear center filler and stop castings constructed in accordance with my invention.

Figure 2 is a central vertical longitudinal sectional view on the line 2—2 of Figure 1, parts thereof being shown in elevation.

Figure 3 is a plan view of a draft rigging with the yoke and cushioning mechanism removed, with parts broken away and shown in section illustrating the spaced relation of 60 the stop members from the center sills.

Figure 4 is a central vertical longitudinal sectional view on the line 4—4 of Figure 3.

Referring to the drawings wherein similar reference characters designate corresponding parts in the several views, the center or draft sills 1—1 are arranged in spaced relation and have extending transversely of the car underframe on either side thereof the bolster 2. The center plate 3 is shown at 3, said plate being connected by rivets to the bottom flanges of the center sills and to the members constituting the bolster. A center bearing is arranged beneath the plate 3 and is provided with an 75 opening through which the king bolts extend into the center thimble 4 formed integral with the center sill tie and stop member 5. A cover plate is shown at 6 and the end sill of the car underframe at 7, the latter being connected by rivets to the cover plate and upper flanges of the center sills, as shown.

The stop member 5 comprises a combined center filler, tie and stop casting connected 85 to the draft sills by means of the rivets 8. Stop lugs 9 are provided on said member and are adapted to be engaged by the rear follower 10 of the cushioning mechanism, the latter being diagrammatically shown in 90 dot and dash lines, as indicated in Figure 2.

The means for spacing the stop casting 6 inwardly of the center sills and at the same time providing for its firm connection thereto, consists of a series of longitudinally 95 disposed bosses 11, and other vertically arranged bosses 12, both groups of said bosses being formed integral with the side walls of the casting and being provided with a plurality of openings through which pass 100

the rivets 8. The engaging faces of the bosses firmly abut against the inner faces of the draft sills, and the relative depth of said bosses determines the spacing of the 5 stop casting inwardly from the sills, as will be understood. The stop members or lugs 9 cooperating with the rear follower 10, are each reinforced by webs or flanges 13 projecting inwardly from the side walls 14 and 10 forwardly of the casting, said flanges acting to brace the stops. I have located the majority of the bosses 11 longitudinally of the casting and at points preferably between the inwardly projecting reinforcing flanges 13 15 so as to permit of the convenient insertion of the rivet connecting means, and to also advantageously obtain the additional reinforcing values of the bosses immediately adjacent the flanges 13. The vertical bosses 20 12 are preferably arranged at or near the rear of the stop casting, the attaching rivets being vertically arranged as distinguished from the longitudinal rows of rivets passing through the bosses 11. The bosses are all 25 preferably of uniform depth sufficient to provide for the advantageous inward spacing of the stop lugs 9 from the center sills. The longitudinally disposed bosses 11 are relatively long, each boss extending from 30 substantially the operative face of the stop lugs to a point well back and over the floor portion of the casting.

Cooperatively associated with and arranged between the inner faces of the draft 35 sills and the outer faces of the wall portions 14 of the stop casting is a reinforcing means composed of an angle bar 15, the vertical flange 16 thereof extending upwardly between the inner face of the center sill and the offset portion of the wall of the stop 40 member, and a horizontal flange 17 of said angle bar projecting beneath an offset portion formed in the floor of the stop casting. The angle bar 15 extends the entire length 45 of the stop member, and is preferably designed to continue rearwardly of the center sills. The horizontal flange 17 is cut away at an angle, as indicated at 18, thereby providing for the necessary clearance for the 50 rear end of the yoke extending between the stop lugs 9. The rivets 8 of the lowermost row pass through the reinforcing bar 15 and firmly unite the walls of the stop member with the center sills.

55 A similarly reinforced stop member 19 is connected by means of rivets 20 to the forward ends of the draft sills, said member including the striking casting 21 and the carry iron support 22. The forward end 60 of the draft rigging recess is closed by the stop casting 19, which serves to firmly connect the draft sills at this point of the draft rigging. The vertical walls of the stop member 19 form cheek plates 23, the 65 rear faces thereof providing stop lugs 24 with which the forward follower 25 of the cushioning mechanism is designed to engage. Bosses 26 are provided on the outer faces of the cheek plates and are adapted to engage with the inner faces of the center 70 sills, said bosses acting to space the stop member inwardly of the sills, as shown. Rivets 20 rigidly connect the front stop member 19 to the center sills, said rivets passing through the bosses 26. The upper 75 boss extends substantially the length of the casting and the lower boss terminates back of the forward end of said upper boss, as shown, the rear ends of each boss being arranged in close proximity to the stop lugs 80 24 of the cheek plates for reinforcing the latter. The several portions forming the stop member 19 are all formed integral, thereby providing a one-piece or unitary member which can be easily connected to 85 the forward ends of the draft sills.

Each cheek plate 19, and more particularly the stop lug 24 formed thereon, is reinforced by means of a top web portion 28 extending from the striking casting to the 90 stop lug, the central portion of said web being partly cut away, as shown in Figure 1. A series of flanges or webs 29 extend rearwardly of the casting uniting the side walls with the stop lugs, the inner faces of said 95 flanges being cut away or inclined, as shown, to provide lateral clearance for the yoke head. Each cheek plate is provided with a relatively long key slot 30, said slot registering with a similar slot 31 formed in each 100 center sill. A coupler key 32 extends through said slots and is arranged to connect the coupler 33 with the forward end of the yoke 34. Slots 35 are provided in the wall portions of the hooded head of the 105 yoke, thereby permitting relative movement of the key therein, but said slots are shorter than the slots 30 in the cheek plates, as shown.

In normal position of the draft rigging, 110 the front edge of the coupler key 32 engages the forward end of the slots 35 in the yoke head, the said key passing through the opening in the coupler which latter closely engages said key, the position of the coupler 115 key in the respective slots 30 and 31 being about intermediate thereof, as shown in Figure 2.

The cushioning mechanism of the draft gear includes the forward follower 25 and 120 the rear follower 10, both of which are adapted to cooperate with the respective stop lugs provided on the spaced stop castings connecting the center sills at each end of the yoke. The respective front and rear 125 stop castings are longitudinally alined, that is, the spacing bosses act to uniformly and inwardly space respective stop lugs 9 and 24 from the center sills, as shown. A draft rigging pocket for car underframes con- 130

structed in accordance with my invention consists of comparatively few parts and those of light weight but maximum strength value, my present association of tie and stop members being particularly useful in connection with cushioning mechanism and a vertical yoke.

I claim:

1. In a draft rigging, the combination with center sills, of a coupler and yoke, cushioning mechanism including follower members, stop castings connected to said center sills, and elongated means furnishing increased cross-sectional areas of metal in the lines of greatest stress imparted to the rivet connections projecting from the castings and contacting the inner opposed faces of the center sills for spacing said castings inwardly thereof, said stop castings bridging the sills and being arranged respectively for engagement by said follower members with the means inwardly spacing the castings disposed in longitudinal alinement.

2. In a draft rigging, the combination with spaced draft sills, of a coupler and yoke, cushioning mechanism including follower members, and stop castings adapted to be normally engaged by said follower members, each of said stop castings being provided with elongated sill engaging bosses acting to inwardly space the wall portions of said stop castings from the draft sills and furnishing increased cross-sectional areas of metal in the lines of concentrated stress imparted to the rivet connections, and a plurality of rivet means extending through said wall portions and each of said bosses and connecting said stop castings to the draft sills.

3. In a draft rigging, the combination with spaced center sills, of a coupler and yoke, cushioning mechanism including forward and rear followers, stop members connected to said center sills, and means including continuous longitudinally extending bosses provided on said stop members contacting the inner faces of the sills for spacing said members therefrom, said bosses having a plurality of openings adapted to receive rivets for connecting the stop members to the sills and being arranged to provide uninterrupted cross sectional areas of maximum thickness longitudinally disposed in the lines of greatest stress imparted to the rivet connections.

4. In a draft rigging, the combination with spaced draft sills, of a coupler and yoke, cushioning mechanism including forward and rear followers, front and rear stop castings connected to said center sills, each of said castings including side wall portions, means inwardly spacing said wall portions from the center sills, said means providing increased cross-sectional areas of metal in the lines of greatest stress imparted to the

rivet connections, stop portions on said castings adapted to be engaged by the followers, said stop and wall portions of the respective castings being longitudinally alined and uniformly spaced from the draft sills.

5. In a draft rigging, the combination with spaced center sills, of a cushioning mechanism, a coupler, a yoke, means including a unitary stop casting bridging and connecting the spaced center sills, said casting having bosses adapted to space the body portion of the casting from the sills, each of said bosses being longitudinally disposed and having a plurality of correspondingly arranged openings, and rivet means passing through said openings for connecting the stop casting to the center sills, the cross sectional area of the bosses between the rivet openings being uniformly maintained throughout the length of said bosses.

6. In a draft rigging, the combination with spaced center sills, of a cushioning mechanism, a coupler, a yoke, means connecting said coupler and yoke, and a one-piece stop casting connected to the center sills and tying the same together, said casting being provided with a plurality of vertically spaced sill engaging bosses adapted to space the casting inwardly of the sills, each of said bosses being provided with a plurality of openings, and rivet means passing through said openings for connecting the stop member to the center sills.

7. In a draft rigging, the combination with spaced center sills, of a cushioning mechanism, a coupler and yoke, means connecting said coupler and yoke, a one-piece stop casting connecting said center sills, said casting having wall portions inwardly spaced from said sills, sill engaging bosses on said wall portions each provided with a plurality of openings, and rivet means passing through said openings and wall portions for connecting the stop casting to the center sills.

8. In a draft rigging, the combination with spaced center sills, of a cushioning mechanism, a coupler and yoke, means connecting said coupler and yoke, a unitary stop casting connecting the center sills, said casting having wall portions, bosses on said wall portions adapted to inwardly space the body of the casting from the sills, said bosses also acting to reinforce said wall portions, and rivet means for connecting said stop casting to said center sills.

9. In a draft rigging, the combination with spaced draft sills, of cushioning mechanism, a yoke and coupler, means connecting said yoke and coupler, a stop casting having integral wall sections having end portions forming stop lugs, spaced webs uniting said wall sections and stop lugs for reinforcing the latter, a plurality of spaced bosses disposed intermediate said webs for

spacing the body of the casting inwardly of the sills, said bosses acting to reinforce said wall sections and formed with a plurality of openings, and rivet means connecting said stop casting to the center sills, said rivet means extending through said bosses and wall sections intermediate said reinforcing webs.

10. In a draft rigging, the combination with spaced draft sills, of a cushioning mechanism including a follower, a yoke and coupler, means connecting said yoke and coupler, and a stop casting having integral wall sections forming stop members for said follower, said wall sections being provided with a series of longitudinally disposed bosses each of which is arranged to receive a plurality of rivet means and adapted to space the stop members inwardly of the center sills.

11. A stop casting for draft rigging adapted to bridge and unite the spaced cen-

ter sills thereof, said casting comprising wall portions, and a plurality of elongated rivet receiving bosses projecting from said wall portions for contacting the inner face of said center sills, said bosses acting to inwardly space the body of the stop casting from said sills and reinforce the same.

12. A stop casting for draft rigging arranged to bridge and unite spaced center sills, said casting including integral wall sections formed with stop portions, inwardly and forwardly extending flanges for reinforcing said wall sections and stop portions, and a series of elongated rivet receiving bosses provided upon the opposite sides of said wall sections and arranged intermediate said reinforcing flanges, the bosses upon the outer faces of said walls acting to inwardly space the body of the casting from the center sills.

In testimony whereof I affix my signature.
IRA O. WRIGHT.
